Fig. 7

Fig. 8

FIG. 1 is a top plan view of a removable cover for culinary vessels embodying our new design.

FIG. 2 is a side elevational view taken along line 2-2 of FIG. 1, with the opposite side being identical.

FIG. 3 is a cross-sectional view in elevation taken along line 3-3 of FIG. 1.

FIG. 4 is an enlarged fragmental sectional view of an end portion of FIG. 3.

FIG. 5 is a bottom plan view.

FIG. 6 is an end elevational view taken along line 6-6 of FIG. 1, with the opposite end being identical.

FIG. 7 is a sectional view in elevation taken along line 7-7 of FIG. 1.

FIG. 8 is an enlarged fragmental sectional view of an end portion of FIG. 7.

We claim:

The ornamental design for a removable cover for culinary vessels, as shown and described.
